UNITED STATES PATENT OFFICE.

WILBER O. PLATT AND JOHN REID, OF OIL CITY, PENNSYLVANIA, ASSIGNORS TO JOSEPH REID GAS ENGINE COMPANY, OF OIL CITY, PENNSYLVANIA, A CORPORATION OF PENNSYLVANIA.

VAPORIZER AND IGNITER FOR INTERNAL-COMBUSTION ENGINES.

1,079,878.

Specification of Letters Patent.

Patented Nov. 25, 1913.

Application filed October 8, 1912. Serial No. 724,588.

To all whom it may concern:

Be it known that we, WILBER O. PLATT and JOHN REID, both citizens of the United States, and residents of Oil City, in the county 5 of Venango and State of Pennsylvania, have invented certain new and useful Improvements in Vaporizers and Igniters for Internal-Combustion Engines, of which the following is a specification.

10 This invention relates to a device to be located within the combustion chamber of an internal combustion engine for the purpose of vaporizing and igniting the fuel, and particularly to that type of such device 15 which will both vaporize and ignite the fuel. spray, and are sufficiently isolated from the cylinder walls and piston, to enable them to take up and retain heat from the repeated combustions sufficient to vaporize or 20 ignite or both vaporize and ignite the fuel.

The object of the present invention is to provide a device of this kind which will be more economical to produce, more effective in operation, more durable under the high 25 temperatures to which it is subjected, and which will be more readily replaceable than devices heretofore constructed.

In carrying out the invention, we employ a vaporizing surface that is made up of a 30 plurality of units in the form of bars, suspended at their ends with their intermediate portions exposed for action; these bars being preferably of cylindrical section, so that they can be constructed from stock material, 35 they will not develop warping effect like plates used for similar purposes, they will afford a greater contact surface for a given area than a solid body or plate, and they are readily removed and replaced when im- 40 paired; moreover, they may be rotated in position to present different portions of their surface to the fuel.

The invention will be fully understood upon reference to the accompanying drawing, in which—

45 Figure 1 is a sectional view of a portion of the cylinder of an internal combustion engine with its contained piston; Figs. 2 and 3 are end views of the piston shown in Fig. 1, Fig. 3 having the vaporizer support to receive the multiple unit vaporizing and body removed; Fig. 4 is a side view of the vaporizer looking from right to left in Fig.

2, and Fig. 5 is a transverse section on the line 5—5, Figs. 1 and 2.

55

1 represents the piston working in the cylinder 2 of an internal combustion engine, operating upon the principle of having its fuel injected through a spray nozzle 3.

4 is the water jacket of the engine.

60

Located upon the end of the piston 1 are a pair of supporting lugs 5 spaced apart to receive the multiple unit vaporizing and igniting body made up of rods 6; said lugs being of sufficient dimensions to isolate the 65 rods 6 from the piston 1, so that said rods can take up and retain heat of one explosion sufficiently to ignite the fuel to produce the next explosion.

To mount the rods 6 on the lugs 5, the 70 latter are provided, on their opposed faces, with grooves 5^a closed at one end to confine

the rods, but open at the other end to admit them; said grooves having at a suitable point intersecting bores 5^b in which a long 75 rod may be introduced and riveted as at 6^c, for the purpose of confining the rods against displacement. The rods 6 may be tubular, but they are preferably solid to increase their heat-storing capacity. They may be 80 of any suitable material but a nickel alloy is preferred in order to reduce oxidation and distortion. They may be of any desired section, but polygonal or circular section is preferred, as the heating surface 85 attainable with a given area is thereby increased and the impact faces are presented in better position for deflecting the sprayed fuel and thereby sub-dividing it and mixing it with the air that is to support combustion. When the multiple unit spraying surface becomes impaired, it is an easy matter to remove one of the ends 6^a of the retaining rod and to remove said rod in order to release the others. The rods are preferably 90 in lateral contact with each other, but they may also be sufficiently loose to be rotated to change the surface presented to the fuel sprayed upon them.

95 We claim:

100 1. In an internal combustion engine, a vaporizer and igniter acting upon the fuel, comprising a plurality of individually detachable rods suspended at both ends in the combustion chamber; said rods accumulat- 105 ing sufficient heat from a previous explosion

to vaporize and ignite the fuel for a subsequent explosion.

2. In an internal combustion engine, a vaporizer and igniter acting upon the fuel, comprising a plurality of individually detachable rods suspended at both ends in the combustion chamber; said rods accumulating sufficient heat from a previous explosion to vaporize and ignite the fuel for a subsequent explosion, and means for suspending said rods, comprising lugs between which said rods are secured.

3. In an internal combustion engine, a vaporizer and igniter acting upon the fuel, comprising a plurality of individually detachable rods suspended at both ends in the combustion chamber, said rods accumulating sufficient heat from a previous explosion to vaporize and ignite the fuel for a subsequent explosion, and means for suspending said rods, comprising lugs having in their opposed faces, grooves receiving the ends of the rods.

4. In an internal combustion engine, a vaporizer and igniter acting upon the fuel, comprising a plurality of rods suspended in the combustion chamber, and means for suspending said rods, comprising lugs having in their opposed faces, grooves receiving the ends of the rods; said grooves being open at one end to admit the rods.

5. In an internal combustion engine, a vaporizer and igniter acting upon the fuel, comprising a plurality of rods suspended in the combustion chamber, and means for suspending said rods, comprising lugs having in their opposed faces, grooves receiving the ends of the rods; said grooves being open at one end to admit the rods; said lugs being recessed transversely to and near one

end of the grooves to admit a confining rod.

6. In an internal combustion engine, a vaporizer and igniter acting upon the fuel, comprising a plurality of detachable rods suspended at both ends in the combustion chamber but unsupported in the middle; said rods being of circular cross section and adapted to accumulate sufficient heat from a previous explosion to vaporize and ignite the fuel for a subsequent explosion.

7. In an internal combustion engine, a vaporizer and igniter acting upon the fuel, comprising a plurality of rods suspended in the combustion chamber and adapted to accumulate sufficient heat from a previous explosion to vaporize and ignite the fuel for a subsequent explosion, and means for suspending said rods at both ends comprising lugs between which said rods are secured; said lugs being located upon the end of the piston.

8. In an internal combustion engine, a piston, lugs projecting from said piston and spaced apart thereon, said lugs being provided with grooves in their opposed faces, rods secured between said lugs with their ends resting in said grooves, and a retaining rod extending through the lugs intersecting the grooves and having its ends enlarged to prevent displacement of the retaining rod.

The foregoing specification signed at Oil City, Pa., this seventeenth day of September, 1912.

WILBER O. PLATT.
JOHN REID.
